METAL BEDSPRING

Hyman Gertler, Montreal, Quebec, Canada

Application August 22, 1944, Serial No. 550,537

5 Claims.

(Cl. 5—201)

This invention relates to all metal bed springs. The conventional bed spring of this type consists of a pair of headers, one at each end, which are separated and held in position by side rails which are rigidly connected at each corner to the headers by means of a malleable iron casting. The arrangement of slats or cables and springs, hereinafter described as the "spring fabric," is connected to the headers and tends to draw them towards each other. A disadvantage of this construction is that under present war conditions the malleable iron castings are no longer available.

The object of the present invention is to provide a connection between the side rails and the headers which dispenses with the conventional malleable cast iron corner, while at the same time permitting ready assembly and taking down of the units so that the side rails, the spring fabric and the headers may be shipped as separate units thereby saving in shipping and storage costs.

A bed spring according to the invention therefore comprises essentially a header at each end, a conventional spring fabric connected to each header and urging the two towards each other, side rails and means connecting the side rails to the headers at the four corners of the bed spring comprising a connector member connected to the header near the end and extending downwardly therefrom, this connector member having a substantially vertical slot formed therein adapted to receive the end of a side rail, each end of each rail being formed, at the side remote from the spring fabric, to engage both sides of the connector member at the bottom of the slot, and, after such engagement to engage the inside of the connector member at the top of the slot at the side of the rail closer to the spring fabric.

According to the preferred modification the side rails are tubular and are flattened at the end to cooperate with a substantially rectangular slot formed in the connector member. At the top corner of each flat portion each of the side rails is cut back to form a shoulder which engages the inside face of the connector member. At the bottom each flat portion is provided with a notch of a size corresponding roughly to the thickness of the connector member and the distance between the base of the notch and the foot of the shoulder is a little less than the length of the slot. The spring fabric holds the connector members against the shoulders and the notches together with the shoulders limit movement of the headers urged by the spring fabric towards each other.

5 The connector member is an angle member having one wing riveted to the header. The other extends substantially parallel to the length of the side rails and has secured thereto a stabilizer member which defines with this wing of the angle member a slot through which the flattened end of a rail passes, the size of the slot being such that the stabilizer member and the wing engage the side rail and prevent lateral and rotary movement of it. According to the preferred modification the stabilizer member is bent at the lower end substantially at right angles and extended laterally of the spring and substantially horizontally to form a corner support adapted to rest on a bed frame. According to a further feature of the invention the wing of the connector member riveted to the header is on the inside and it is longer than the other wing so that it extends down inside the part of the bed frame on which the corner support rests thereby preventing the spring from sliding off the bed. A protective cover is provided secured at the top to the underside of the header and at the bottom to the top side of the corner support.

15 25 The invention will now be described with reference to the accompanying drawings in which

Figure 1 is a perspective view showing the end of a side rail assembled with the connector member, the stabilizer and corner support, and the protective cover.

30 Figure 2 is a view of the components shown in Figure 1, plus a broken-away portion of a header taken from the broken-away end of the side rail shown in Figure 1.

35 Figure 3 is a side view of the components shown in Figure 2 taken from the right, parts being cut away, the connection of a conventional tension spring being shown, and the end of the side rail and the adjacent parts of the connector member being shown in section, and

40 Figure 4 is a perspective view on a reduced scale of the connector member.

45 Figure 5 is a plan view of an assembled bed spring;

Figure 6 is an enlarged section on the line 6—6 in Figure 5 with the spring fabric removed, and the side members of a bed frame shown in dotted lines; and

50 Figure 7 is a section on the line 7—7 of Figure 6 showing in dotted lines the position of the header.

As appears most clearly from Figure 3 the header 10 is the conventional right angle member formed at the front edge with a plurality of holes 12 in each of which is hooked a tension spring 14.

connected at its other end to slats or cables 13. Near to each end of each header is connected a downwardly extending angle member 14 the wing 15 of which extends substantially parallel to the length of the bed spring. The wing 16 of the angle member 14 (herein described as a connector member) is connected to the header by means of rivet 17 in known manner.

The side rails 18 are of tubular steel and are flattened at the ends (see Figure 1) to correspond approximately to a rectangular slot 19 formed in the wing 16 of the member 14 and arranged with its longitudinal axis running straight up and down.

Referring to Figure 3 it will be seen that the top corner of the flattened end of the side rail 18 is cut back to form a shoulder 20 and that the bottom of the flattened end of the side rail 18 is provided with a notch 21 corresponding approximately in width to the thickness of the angle member 14. The length of the slot 19 is slightly greater than the distance between the base of the notch 21 and the foot of the shoulder 20 and the remaining top corner is rounded. Thus the bottom corner of the side rails may first be inserted through the slot until the portion of the member 14 defining the bottom of the slot 19 is engaged in the notch 21.

The side rail 18 is then lifted to the position shown in Figure 3 with the shoulder 20 bearing against the inside face of the portion of the member 14 which defines the top of the slot 19. The springs 12 and slats 13, having been assembled in position, hold the members 14 against the shoulders 20 and the shoulders 20 and notches 21 engaging the members 14 prevent the headers from being pulled toward each other. There is thus provided an effective and secure connection between the side rails and the headers which is made more rigid when weight, which tends to draw the headers towards each other, is placed on the slats 13.

The slot 19 is formed in the wing 16 close to the wing 15. Thus the flat portion of the end of the side rail 18 contacts the wing 15 and when the complete spring is assembled there can be little side sway or twisting, i.e. lateral or rotary movement of the side rails. Such movement is eliminated by a stabilizer 22 secured to the wing 15 by rivets 23 and shaped to define between it and the wing 15 a slot which permits passage of the flattened end of the side rail 18 but is narrow enough for the stabilizer 22 and wing 15 to engage the tapered portion of the side rail sufficiently firmly to substantially eliminate any lateral or rotary movement of the side rail in relation to the wing 15. As appears from Figures 2 and 6 the length of the slot defined between the stabilizer 22 and the wing 15 is greater than the width of the flattened end of the side rail, and as noted above the remaining top corner of the flattened end of a side rail is rounded off. This to allow for the fact that the bottom corner of the end of the side rail as shown in Figure 3, must be inserted in the slot 19 first so that the member 14 may be engaged by the notch 21 and thereafter the side rail must be raised to the position shown in Figure 3 in which shoulder 20 engages the inside face of wing 16 at the top of slat 19.

The lower end of the stabilizer 22 is provided with an extension 24 running at right angles to the main part of the stabilizer and towards the sides of the bed spring in order to provide a corner support adapted to rest on a bed frame. As appears from the drawings the wing 16 is longer

than the wing 15 of the member 14 so that the former extends down along the inside of the portion of a bed frame on which the extension 24 rests, and thereby prevents the bed spring from sliding off the bed.

In order to improve the appearance of the corner and to prevent bed clothes and the like from being caught, a protective corner member 25 is welded at the bottom to the top face of the extension 24 and at the top to the bottom face of the horizontal wing of header 10.

It will be appreciated that the wing 16 of the member 14 need not necessarily be straight as shown but may be formed into an S or similar shape.

I claim:

1. A bed spring having two headers, one at each end, spring means urging said headers towards each other, two tubular side rails each flattened at each end, and means connecting said rails to the headers, said means comprising an angle connector member extending downwardly from each header near each end, and having one wing connected to the header and the other wing extending therefrom substantially in the direction of the length of the bed, the wing connected to the header having formed therein near to its junction with the other wing a substantially rectangular slot having its longitudinal axis substantially in the vertical plane and adapted to receive the flattened end of a side rail, said side rail being notched at the bottom to engage both faces of the wing connected to the header at the bottom of said slot, and formed at the top of the flattened end with a shoulder adapted to engage the inside face of said wing at the top of the said slot after engagement of both sides of the connector member at the bottom of the slot, and a stabilizing member secured to the wing of the connector member which extends in the direction of the length of the bed, said stabilizer defining with said wing a slot through which the flattened end of a rail passes, and engaging said rail to prevent lateral and rotary movement thereof.

2. A bed spring as defined in claim 1 in which said stabilizing member is provided with a lateral and substantially horizontal extension forming a corner support adapted to rest on a bed frame.

3. A bed spring as defined in claim 1 in which said stabilizing member is provided with a lateral and substantially horizontal extension forming a corner support adapted to rest on a bed frame, and the wing of the connector member which is connected to the header extends below said corner support and is adapted to fit inside the bed frame on which the corner support rests to prevent the bed spring sliding off the bed frame.

4. A bed spring as defined in claim 1 in which said stabilizing member is provided with a lateral and substantially horizontal extension forming a corner support adapted to rest on a bed frame, and a protective cover member secured outside of each side rail and to the underside of a header and to the top side of a stabilizing member.

5. A bed spring having two headers, one at each end, spring means urging said headers towards each other, two tubular side rails each flattened at each end and means connecting said rails to the headers, said means comprising an angle connector member extending downwardly from each header near each end, and having one wing connected to the header and the other wing extending therefrom substantially in the direction of the length of the bed, the wing connected to the header having formed therein near to its

junction with the other wing a substantially rectangular slot having its longitudinal axis substantially in the vertical plane and adapted to receive the flattened end of a side rail, said side rail being notched in the bottom edge near the end to receive and engage both faces of the wing connected to the header at the bottom of the said

slot, and having the top corner cut away to permit engagement of said wing by the notched bottom edge and subsequent positioning of said side rail, and to form a shoulder adapted to engage the inside face of the top of the connector member at the top of the said slot.

HYMAN GERTLER.
